I. J. VETTER

PHONOGRAPH OR OTHER SOUND PRODUCER OR REPRODUCER

Filed May 29, 1922

INVENTOR

Ignatius J. Vetter

UNITED STATES PATENT OFFICE.

IGNATIUS J. VETTER, OF NEW YORK, N. Y.

PHONOGRAPH OR OTHER SOUND PRODUCER OR REPRODUCER.

Application filed May 29, 1922. Serial No. 564,845.

To all whom it may concern:

Be it known that I, IGNATIUS J. VETTER, a citizen of the United States, residing at New York city, in the county of New York and State of New York, have invented new Phonograph or Other Sound Producers or Reproducers, of which the following is a specification.

My invention relates to improvements in phonographs; and the objects of my improvements are; first, to provide a horn that will vibrate to the slightest tone; second, to carry the vibrations of the horn into, or play them upon a suitable resonator or amplifier operating to modify or improve the tone quality as well as increase the volume of sound and consisting preferably of a hollow casing like the body of a violin or similar musical instrument; and, third, providing a cabinet in which the sound emanates evenly from all sides eliminating the harsh effect of the horn.

I attain these objects by the mechanism illustrated in the accompanying drawing, in which—

Figure 1 is a plan view of that part of the phonograph relating to my invention.

Figure 2 is a vertical bisectinal view, also showing the relative position of the motor M, turn-table, T, and tone-arm, L, to my invention:

Figure 3 is a detailed view in perspective of the horn D, showing its inner construction:

Figure 4 is a view in perspective of one of the instruments, I:

Figure 5 is a perspective view of one of the vibration carriers, referred to herein-after as (carriers) H.

Similar letters refer to similar parts throughout the several views.

In Figure 2, the table A, with its standards or legs, B of which there are four, and the bottom C, constitute the frame-work of the phonograph.

The outer walls of the horn D, Figure 3, may be made of any vibrant material. I prefer to use seasoned spruce for the walls. The vibrating rack E, inside of the horn, I prefer to make of seasoned spruce boards f, superposed and running parallel to the sides n, n of horn but spaced apart. The sounding boards of the bank or rack are held together and spaced by dowels or posts d, which pass through and are glued to the boards. These posts or dowels extend be-

yond the boards and engage or press against the sides n, n of the horn. These boards do not come in direct contact with the horn at any point, thus permitting them to vibrate to the slightest tone. The sound posts or dowels d, carry the vibrations to the sides n, n of the horn so that the vibrations of the sound boards will reinforce the vibrations of the sides of the horn by acting in acoustic synchronism with them. The number of these boards may be varied at will. In general the number depends upon the size and construction of the horn. The bank of sounding boards may be supported and held in position in the horn by the posts d or any suitable means.

The sides or walls n, n, of the horn may be perforated at intervals with holes or openings k. These holes may be of different sizes, small at the upper end and larger at the lower end, permitting some of the sound to pass through eliminating any harshness of tone. They may be located irregularly.

The horn D, is bolted to table A, as shown in Figure 2, directly under tone-arm opening u, permitting it to hang and vibrate like a bell.

In Figure 1, and Figure 2, b, b, b, b, are bars or cleats passing across and extending beyond sides n, n of the horn. The ends of the cleats are bored through permitting bolts or rods e, e, e, e, to pass through. The cleats are fastened to, and touch only at the corners of, the horn, the center being cut away so as not to interfere with the vibrations of the walls of the horn.

The instrument I, Figure 4, of which one or more may be used is hollow and is intended to act as a resonator reinforcer or modifier of the sounds. Its face m, may be made of seasoned spruce, and is provided preferably with openings or holes, as in instruments of the violin type. Posts i, i which are glued to top and bottom of instrument, serve to hold it in place.

I prefer to use two of these resonator instruments placed in position as shown in Figure 2: p, p are the sound-posts inside II of the instruments of which one or more may be used. These posts serve to brace the face of the instrument to resist pressure. Cleats o, o, o, o are fastened on the back of the instruments I, and are substantially the same as cleats b on horn D. Bolts e, e, e, e, Fig. 2, pass through cleats b, b, b, b, on horn and through cleats o, o, o, o, on resonator

instruments I. Tightening nuts or thumbscrews r, r, r, r , are placed at the ends of these bolts e, e, e, e .

The board J, in Figure 2, serves as a base 5 for the instruments I engaged therewith by posts i, i , and also prevents any reflection of sound. This board passes around horn leaving an air space on all sides so as not to interfere with the vibrations, the horn being 10 fastened to it only at its corners to prevent it from shifting.

The carrier H, Figure 5, may be made of any vibrant material. I prefer to use a bank 15 of spruce boards x , running parallel to each other, and held together in spaced relation by dowels or posts s, y, t , which pass through, and are glued to the boards: any 20 number of these boards may be used. The sound posts or dowels s, s, s, s , at both ends 25 of the carriers extend beyond the boards on one side and the sound posts or dowels t, t , extend beyond the boards on opposite side as shown.

In Figure 2, two of these carriers are 30 used, placed in position as shown between the walls of the horn and the resonators or 35 amplifiers I. The posts or dowels s, s, s, s , being placed against the horn those at the upper end are longer than those at the lower end, so as to conform with the angle of the horn, and keep the carriers in an upright 40 position, and the posts or dowels t, t , are placed against the resonator instruments 45 preferably against the face thereof, the whole acting as a bridge.

By tightening the thumbscrews, r, r, r, r , a tension is put on the carriers and on the 50 sides of the horn and the posts d of the rack within the horn and the sound vibrations are 55 carried into, or play upon the resonator or amplifier instruments I.

As will be seen, the vibrations of the sides 60 of the horn due to the air vibrations within the same, are carried into the bank H and 65 there amplified by the sound board or boards composing the same, whence they are conveyed to the resonators I by means of the dowels or posts s, y, t , and by the resonators 70 are still further amplified or modified to produce a louder and improved effect. Also, 75 and as will be fully apparent from the construction, further amplification of the sound will result from the fact that the sound vibrations of the sound board or rack E being 80 communicated directly to the side of the horn through the vibrational or acoustic connection therewith, will reinforce the vibrations of the horn itself by acting in acoustic synchronism therewith and the reinforced vibrations thus set up will be transferred 85 into the bank or boards comprising the carrier and sound board H wherein they are further reinforced and amplified and conveyed to the resonators. The resultant effect is a very great amplitude or volume

of sound reproduction due to the combined acoustic effect of all the parts placed in sound vibrational or acoustic relation to one another by the construction described.

This effect may be produced by building 70 the instruments into, or as part of the cabinet and getting a tension on the carriers by a screw device on the dowels t, t , of the carriers, but I prefer to carry out this effect as shown in the drawing in which, the horn, 75 the resonators and the carriers are all independent parts and can easily be replaced if necessary.

In Figure 2, P, is a pyramid, having a 80 square base. This pyramid conforms to the shape of the mouth of the horn and extends partially within the same and serves to spread the sound evenly on all sides. It also serves as a damper. This pyramid is not fastened to the bottom, but is independent 85 and may be so constructed that by any suitable device it can be raised so as to partially or entirely close the horn, moderating the volume of sound.

When the horn is entirely closed at the 90 bottom the tone is softened, but, the sound vibrations playing upon the instruments prevent any stifling effect.

All sides of the cabinet or casing of the 95 instrument may consist of cut out panels of any design, backed up with silk or any light weight fabric that will permit the sound to pass through. These panels may be placed in separate frames so that they can easily be removed.

The use of a plurality of resonators of 100 different size or natural reinforcing effect and all responsive to the vibrations received from the record through the tone arm by the means described or any other suitable 105 means is not herein claimed as it forms the subject of claims in an application for patent filed by me January 28, 1924, as a division of the present application. Nor do I 110 claim herein the use of the rack of sound boards E within the enclosure into which the tone arm delivers the sounds directly and as used for superadding vibrations to and reinforcing the effects of the intermediate rack H upon the resonator inasmuch as 115 this is broadly claimed, together with the constructions whereby the reinforcing action is effected, in said divisional application.

I do not claim anything new in the reproduction of records, and, I am aware that prior to my invention, phonographs have been made, combining motor, turn-table, reproducer, tone-arm and horn, in a cabinet: I therefore, do not claim such a combination 125 broadly, but

I claim:

1. In a sound reproducer, the combination with a horn, of sound boards provided with sound posts and a resonator vibrationally 130

connected with the horn by said sound posts engaging the horn and the resonator respectively.

2. In a sound reproducer, the combination with a horn and a resonator, of a sound carrier comprising boards of vibrant material superposed and separated from one another but in solid vibrational connection with one another and sound transferring posts extending therefrom into vibrational engagement respectively with the side of the horn and the side of the resonator.

3. In a sound reproducing instrument, the combination of a horn, a resonator, an intermediate vibrational carrier comprising a bank of boards provided with sound posts between the resonator and horn and means connecting the horn and resonator for placing tension on the carrier.

4. In a sound reproducing instrument, the combination of a horn, a resonator, an intermediate vibrational carrier having posts engaging respectively the side wall of the horn and a face of the resonator, cleats on the horn and resonator and means for drawing the cleats together to put tension on the carrier.

5. In a sound reproducing instrument, the combination of a horn, a resonator, a vibrational carrier interposed between them for transferring the vibrations of a side wall of the horn to a face of the resonator, cross-bars or cleats passing across the horn and the resonator respectively and touching the same only at the corners and means for drawing the cleats together to put tension on the carrier.

6. In a sound reproducing instrument, the combination of a horn, a resonator, a vibrational carrier interposed between them for transferring the vibrations of a side wall of the horn to a face of the resonator, cross-bars or cleats passing across the horn and the resonator respectively and touching the same only at the corners, rods or bolts passing through said bars and tightening means applied to said bars to draw the horn and resonator against the intermediate carrier.

7. In a sound reproducing instrument, the combination of a horn, a resonator, and an intermediate carrier consisting of a bank of sound boards held together in spaced relation by suitable sound posts and having posts extending into engagement with a side wall of the horn and into engagement with a face of the resonator.

8. In a sound reproducing instrument, the combination with a horn and a resonator, of an intermediate bank of sound boards held together and spaced apart by posts and having posts near its edge and at or near its center engaging respectively a side wall of the horn and a face of the resonator.

9. In a sound reproducing instrument, the combination of a horn, a resonator and an intermediate vibration rack consisting of a series of sound boards spaced apart and having means whereby they are vibrationally engaged with a side of the horn and a side of the resonator.

10. In a sound reproducing instrument, the combination of a horn, a resonator and an intermediate sound board having sound transferring posts engaged respectively with a side of the horn and a side of the resonator.

11. In a sound reproducing instrument, the combination of a horn, a sound box or resonator held in place by posts projecting from its ends parallel with its face and a sound board having posts vibrationally connecting the side of the horn with a face of the sound box.

12. In a sound reproducing instrument, the combination of a horn, a resonator box, a vibrational carrier consisting of a bank of sound boards and posts projecting therefrom, said carrier being interposed between and engaging a wall of the box and a side of the horn and means for securing tension on said vibrational carrier connecting the horn and box.

IGNATIUS J. VETTER.
